UNITED STATES PATENT OFFICE

160,732

TRAILER WINDOW UNIT

David L. Painter, Evanston, Ill.

Application April 28, 1949, Serial No. 2,323

Term of patent 14 years

(Cl. D14—27)

To all whom it may concern:

Be it known that I, David L. Painter, a citizen of the United States, residing at Evanston, county of Cook, and State of Illinois, have invented a new, original, and ornamental Design for Trailer Window Unit, of which the following is a specification, reference being had to the portion of the accompanying drawing in solid lines, forming a part thereof, in which:

Figure 1 is a plan view of the front portion of a trailer showing my window design as viewed from the top; Fig. 2 is a perspective view of the front portion of a trailer body showing my window design as viewed from a position to the front and right of the trailer; and Fig. 3 is a perspective view of the front portion of the trailer showing my window design as viewed from a position to the front and left of the trailer.

The dotted line showing in the several drawing figures is for illustrative purposes only.

I claim:

The ornamental design for trailer window unit, as shown.

DAVID L. PAINTER.
